UNITED STATES PATENT OFFICE.

LELIA E. HATHAWAY, OF WELLSBORO, PENNSYLVANIA, ADMINISTRATRIX
OF GEORGE M. HATHAWAY, DECEASED, ASSIGNOR TO HATHAMITE
COMPANY, OF WELLSBORO, PENNSYLVANIA.

EXPLOSIVE COMPOUND.

No. 815,821.

Specification of Letters Patent.

Patented March 20, 1906.

Application filed November 27, 1903. Renewed August 19, 1905. Serial No. 274,962.

To all whom it may concern:

Be it known that GEORGE M. HATHAWAY, deceased, late a citizen of the United States, and a resident of Wellsboro, in the county of 5 Tioga and State of Pennsylvania, did invent a new and useful Explosive Mixture or Compound, of which the following is a specification.

The invention relates to explosives; and it 10 has for its object the production of a mixture or compound which under any ordinary condition of temperature and regulation of any shock to which it may or can be subjected during its manufacture, transportation, storage, or handling is an enduring and unexplosive combination of combustible substances, but which at the will of the operator may instantaneously be converted into a convenient and effective high explosive of immense 15 destructive power, yielding on combustion absolutely harmless gases.

The invention consists generally of a mixture or compound of certain non-explosive ingredients which are mechanically assembled in such proportions and under such conditions as to produce a safe product answering to all the requirements of practical use and incapable of being exploded in any other way than by the use of a quick-acting detonator, such as fulminate of mercury.

More specifically, the invention consists of an explosive in which an oxidizing agent, such as a metallic nitrate, and a sensitive agent, such as a mono or dinitro phenol, are 25 combined, either separately or jointly, with a hydrocarbon, collodion, and carbon.

The compound or mixture as a whole comprises the following ingredients, viz: barium nitrate, seven pounds; paraffin, six parts, 30 benzene, one part, one pound; mono or dinitro phenol, seven and one-eighth pounds; collodion, seven and one-fourth pounds; pulverized wood-charcoal, one-half pound; paraffin-oil, three-fourths pound. These ingredients are treated and combined in the 35 following manner, viz: The barium nitrate or other metallic nitrate is heated to 130° Fahrenheit to drive off all moisture. The paraffin or other hydrocarbon and the benzene are mixed together, and about one 40 pound of this mixture is added to the barium

nitrate, the oxidizing agent. The hydrocarbon and the oxidizing agent are mixed together until thoroughly dry and will be designated as "mixture No. 1." The dinitrophenol, which is the sensitive agent, and the collodion are mixed together until thoroughly dry, and this mixture is designated "No. 2." Mixtures 1 and 2 are then mixed together, and when thoroughly mixed the pulverized 45 charcoal is added and the whole mass mixed together, after which the paraffin-oil is added. As thus mixed and compounded the mixture can be melted and poured into shells or projectiles, and thus all danger of the explosive 50 "listing" when fired from a gun is avoided, as the mass at once hardens. The explosive thus melted and poured into the shell can be kept for an indefinite length of time without losing any of its explosive force.

For commercial purposes the uses of the mixture are practically without limit. Its qualities will best assert themselves in deep-shaft mining, where the disadvantages of other explosives are most apparent. The 55 great explosive power of the mixture makes it especially applicable to the demands of mining in mountainous districts where rock of unusual hardness is encountered, while the 60 perfect safety with which it can be handled 65 will solve a great many problems for the miners in those districts. The absolute immunity of the mixture from the effects of changes in temperature renders it equally as effective in countries where the climate is 70 cold as it is in those countries where the climate is warmer. In fact, it retains its original explosive force under any and all conditions, and any attempt to explode it by any 75 means other than by fulminate of mercury 80 has proven absolutely unsuccessful.

If for some uses a less powerful explosive should be required, the explosive strength of the mixture herein described may be decreased by increasing the quantity of barium 90 nitrate employed, in which case the added barium nitrate acts as a retarding element.

Having thus fully described the invention, what is claimed as new is—

1. An explosive containing an oxidizing agent, paraffin, benzene, and dinitrophenol.
2. An explosive containing an oxidizing

agent, paraffin, benzene, dinitrophenol, and collodion.

3. An explosive containing an oxidizing agent, paraffin, benzene, dinitrophenol, collodion, and carbon.

4. An explosive containing a metallic nitrate, dinitrophenol, collodion, carbon, and a hydrocarbon.

5. An explosive containing a metallic nitrate, dinitrophenol, collodion, pulverized wood-charcoal, and a hydrocarbon.

6. An explosive containing a metallic nitrate, dinitrophenol, collodion, carbon, and paraffin.

15 7. An explosive containing barium nitrate,

paraffin, dinitrophenol, carbon, and paraffin-oil.

8. An explosive containing barium nitrate, paraffin, dinitrophenol, collodion, pulverized wood-charcoal, and paraffin-oil.

In testimony whereof I have hereunto signed my name to this specification in the presence of two subscribing witnesses.

LELIA E. HATHAWAY,
Administratrix of the estate of George M. Hathaway, deceased.
